REFRIGERATING APPARATUS

Earl D. Drake, Grand Rapids, Mich., assignor to
 Nash-Kelvinator Corporation, Detroit, Mich., a
 corporation of Maryland

Application February 28, 1942, Serial No. 432,732

1 Claim. (Cl. 220—9)

The present invention relates to refrigeration apparatus and more particularly to an improved cabinet structure.

It is an object of the present invention to provide an improved arrangement for securing breaker strips to metal walls of a refrigerator cabinet.

It is another object of the present invention to join the edges of the inner and outer walls of a refrigerator cabinet by breaker strips which are readily attached thereto by use of resilient members.

It is a further object of the present invention to arrange the breaker strips along the front wall of the cabinet adjacent to the door opening and provide means for locking the breaker strips in alignment with the edge of the door opening.

The invention itself, however, both as to its organization and its operation, together with additional objects and advantages thereof, will best be understood from the following description of specific embodiments when read in conjunction with the accompanying drawings, in which:

In the drawings:

Fig. 1 is a front elevational view of a refrigerator cabinet, with parts broken away, embodying features of the present invention;

Fig. 2 is a fragmentary cross-sectional view taken along line 2—2 of Fig. 1;

Fig. 3 is a perspective view of a securing member;

Fig. 4 is a fragmentary front view with parts broken away and parts shown in section of a corner of the refrigerator cabinet;

Fig. 5 is a fragmentary cross-sectional view taken along line 5—5 of Fig. 4;

Fig. 6 is a fragmentary cross-sectional view taken along line 6—6 of Fig. 5;

Fig. 7 is a cross-sectional view taken along line 7—7 of Fig. 6; and

Fig. 8 is a perspective view of another securing member used in the present invention.

Shown in the drawings is a refrigerator cabinet 20 having a food storage compartment 22. Access to the food storage compartment is through opening 24 closed by a swingably mounted door 25. The door 25 is provided with a gasket 26 for sealing against the front wall of the cabinet immediately adjacent to the opening 24 to prevent air entering the food storage compartment. The circulating air in the compartment 22 is cooled by a suitable refrigeration unit (not shown).

The refrigerator cabinet 20 comprises an outer sheet metal casing or shell 30 and an inner sheet

metal casing or liner 32. The liner 32 forms the walls or sides of the food storage compartment and are spaced from the sides or walls of the outer shell 30 for the interposition of suitable heat insulation material 34 therebetween.

The outer casing or shell 30 is formed to provide the sides, top and, if desired, the rear wall of the cabinet. The forward marginal edge of the shell 30 is bent at right angles to respective side and top to form a front wall portion 36. The portion 36 is provided with extended metal which is doubled upon the portion 36 and continued rearwardly along the sides and top portion of the shell a determinable distance to be then bent to extend the remaining portion thereof parallel to the front wall portion 36 forming a rear wall portion 37. The rear wall portion 37 forms with the front wall portion 36 a pocket or recess 39. This form of construction reinforceably strengthens the front wall of the cabinet.

The inner liner 32 is formed with a laterally extending flange about the door opening 24 to form a front wall portion 40 which is in substantial parallel alignment with the front wall portion 36 of the outer shell. The front wall portions 36 and 40 terminate to provide a substantial spatial gap between their edges. The marginal edge portion of the front wall 40 is bent to form a rearwardly extending flange 42 which extends in spaced relation to the sides of the liner 32.

The liner 32 is supportingly secured at each of its four corners to the outer shell 30. The corners are similarly constructed and arranged, therefore, there is only shown the construction and arrangement for corner 44 which comprises an ear 44 secured to the rear face of the front wall portion 40 of the liner 32 by weld or the like. Secured to and extending diagonally across the corner of the outer shell 30 is a gusset member 46. The ends of the gusset member 46 are secured by weld or the like to the rear wall portion 37. Ear 44 is secured by screw 45 to gusset member 46, and held in spaced apart relation by a heat insulation spacer 47 interposed therebetween.

Joining the front walls 36 and 40 is a breaker strip 50 confined on one edge thereof to the pocket 39 and the other edge in flush contact with the wall portion 40. The breaker strip may be made of plastic, fibrous material, "Bakelite" or other suitable non-hygroscopic non-metallic material. A similar breaker strip is positioned along the other side of the cabinet on the front wall 40 adjacent the opening 24 thereof, and a breaker

strip 52 immediately above the food storage compartment at the top of the cabinet, and breaker strip 53 immediately below the food storage compartment. Since the principle of attaching the breaker strip 50 to the cabinet, and the principle of attaching the other breaker strips including breaker strips 52 and 53 are the same, there is only shown in detail the breaker strip 50 and the way it is attached to the cabinet.

Formed in the breaker strip 50 on the rear face thereof are spaced apart parallel grooves 56 having inclined sides 57. Receivable in the grooves 56 are turned ends or fingers 61 of resilient member 60. The ends 61 are connected by body portion 62 which is arcuated and formed of resilient material so as to normally tend to draw the ends 61 towards each other thereby causing each end 61 to frictionally engage an inclined side 57 of its respective groove 56 for gripping the breaker strip. The grooves extend longitudinally the length of the breaker strip thereby permitting the attachment of the resilient members at spaced apart intervals as desired therealong. Formed from the body portion 62 and extending upwardly and outwardly therefrom is an arm 64 adapted to engage the flange 42 of the liner 32.

The breaker strip is assembled by insertion of one edge into the pocket 39 and then drawn sufficiently forwardly for the arm 64 to engage over the flange 42. The engagement of the arm 64 plus the resiliency of the member 60 tends to urge and maintain one edge of the breaker strip in flush contact with the front wall portion 40. The opposite end of the breaker strip is urged towards and held in contact with the edge of the outer shell by resilient member 67 attached to the rear wall portion 37. A plurality of members 67 may be attached along the wall as is found desirable for holding the edge of the breaker strip to the edge of the front wall 36.

In the assembling and securing of the breaker strips to the cabinet it is desirable that the longitudinal edge of the breaker strips adjacent to the opening 24 be in parallel alignment with the edge of the opening 24. Secured by screw 70 to gusset member 46 is a member 72 having a longitudinal edge bent to form a tongue 74 receivable in groove 75 formed in the breaker strip 50. A laterally extending tongue 76 is formed along the top of the member 72 and is receivable in groove 77 formed in the breaker strip 52. The tongues 74 and 76 are formed to extend at right angles to each other. The grooves 75 and 77 are each formed to extend parallel to a longitudinal edge of the breaker strip. The engagement of tongue 74 in groove 75, and tongue 76 in groove 77 the breaker strips 50 and 52 are aligned to extend at right angles to each other in conformity to the edge of the door opening. The edges of the breaker strips extend in space parallel relation to the edge of the door opening. It will appear obvious that the angularity of the tongues, or the direction of the grooves may be varied should a different pattern or arrangement of the breaker strips be desired. The member 72 permits the alignment of the breaker

strips relative to each other and also serves to lock them in fixed relation. Similar securing members (not shown) are used for securing and aligning the opposite ends of the breaker strips 50 and 52 with breaker strips extending along the other sides of the door opening.

It will be apparent that, if desired, the breaker strips may be individually aligned and secured by members 72 which may be formed with but a single tongue.

Corner trim strips 90 are provided to extend across the gap between and to join adjacent breaker strips. The strips 90 comprise a portion 92 which extends across the face sections of the breaker strip having one end receivable in the pocket 39 and the opposite end bent to form a corner connecting section 94 with its end 95 inserted between the breaker strips and the front wall portion 40. The corner strips 90 is frictionally held by the pressure of the breaker strips against the walls 36 and 40.

In attaching the member 60 to the breaker strips pressure is applied upon the back of portion 62 to draw the ends 61 sufficiently apart to enter a respective groove 56. Upon release of the pressure the ends 61 will frictionally engage an inclined side 57 by the outward flexing of the back portion 62. By the arrangement of the finger 64 and its engagement over the edge of the flange 42 the back portion 62 will be maintained in an outwardly flexed condition preventing release of the breaker strip. The finger 64 is also tensioned in its engagement with the flange 42 so as to draw the breaker strip in flush contact with the front wall 40. Shifting or lateral movement of the breaker strip being prevented by the member 72.

While I have shown and described the preferred form of my invention, I do not wish to limit myself to the precise detail as shown and described, but wish to avail myself of such variations and modifications as may come within the scope of the appended claim.

I claim:

45. A cabinet construction, comprising inner and outer shells having the edge portions thereof bent inwardly toward each other, the edge portion of the outer shell being bent to form a pocket opening toward the edge portion of the inner shell, an inturned flange extending rearwardly from said edge portion of the inner shell, a breaker strip bridging the space between said edge portions of the inner and outer shells, and having grooves formed on the inner surface thereof, a bowed resilient member provided with fingers engaging said grooves for attaching said member to said breaker strip, an outwardly extending arm on said resilient member, said breaker strip having, in operative position, an edge thereof inserted in 50 said pocket and said arm of said resilient member engaging over said inturned flange and subjecting said arm to tension for maintaining said resilient member in a bowed condition to cause the fingers thereof to grip said breaker strip and to 55 urge said breaker strip into engagement with said edge portion of said inner shell.

EARL D. DRAKE.
